TAPE RECORDING AND PLAYBACK MACHINE

Robert Podall, Highland Park, Ill., assignor to Sound,
Inc., Chicago, Ill., a corporation of Illinois

Application July 6, 1959, Serial No. 56,659

Term of patent 14 years

(Cl. D26—14)

FIG. 1

FIG. 2

Des. 187,228

PAGE 2

FIG. 3

FIG. 4

FIG. 5

FIG. 6

Fig. 1 is a perspective view of a tape recording and playback machine showing my new design.

Fig. 2 is a top plan view of the same.

Fig. 3 is a front elevational view of the same.

Fig. 4 is a side elevational view of the same taken from the left side as viewed in Fig. 3.

Fig. 5 is a side elevational view of the same taken from the right side as viewed in Fig. 3.

Fig. 6 is a perspective view similar to that of Fig. 1 but with a cover placed thereon.

I claim:

The ornamental design for a tape recording and playback machine, substantially as shown.
